UNITED STATES PATENT OFFICE.

HENRY W. PLEISTER, OF WESTFIELD, NEW JERSEY, ASSIGNOR TO HENRY B. NEWHALL;
HENRY B. NEWHALL, JR., EXECUTOR OF SAID HENRY B. NEWHALL, DECEASED.

RAIL-TIE EXPANSION.

1,295,589.

Specification of Letters Patent. Patented Feb. 25, 1919.

Original application filed October 2, 1915, Serial No. 53,749. Divided and this application filed December 19, 1916. Serial No. 137,759.

To all whom it may concern:

Be it known that I, HENRY W. PLEISTER, a citizen of the United States, and a resident of Westfield, in the county of Union 5 and State of New Jersey, have invented certain new and useful Improvements in Rail-Tie Expansions, of which the following is a specification, taken in connection with the accompanying drawings, which form a part 10 of the same.

This case is a division of my copending application for rail tie expansion, Ser. No. 53,749 filed October 2, 1915.

My invention relates to a rail tie expansion for securing railroad rails to ties.

It is well known that in untreated and soft wood ties the common drive spike tears and breaks the fiber of the wood when it is driven into the tie. Such drive spikes do 20 not have a firm engagement, throughout their length, with the fiber of the tie. Traffic over the rails, whether the road be curved or straight throws great longitudinal strain upon the spike, which tends to lift it out of 25 its hole in the tie. On curves the spike, in addition to resisting the upward pull of the rail as the rolling load passes over it, also has to resist tremendous lateral strains, which tend to enlarge the hole in which the 30 spike is mounted. Where these lateral and longitudinal strains are thrown upon the spike they render even a new tie unserviceable in a comparatively short time.

With such spikes water rapidly leaks into 35 the hole, resulting in rotting and deterioration of the already lacerated fiber of the tie. It is well known that track walkers and section gangs are continually driving back such loosened spikes and respiking the ties.

In ties which have been treated with some preservatives, as for example, creosote, it has been found that the life of such a tie would be greatly prolonged but for the local deterioration of the tie due to spiking and 45 respiking. It is only on a comparatively small area of the tie that spikes can be applied. Such treated ties are comparatively expensive, and the necessity of discarding them simply because they have become unserviceable from spiking and respiking is a considerable expense in railroad upkeep.

To lengthen the life of such a tie screw spikes are sometimes used which give a longer life to the tie than the drive spikes.

In England the practice has developed of

bolting all the way through the tie. This is very expensive as the underside of the tie is inaccessible.

One of the results accomplished by my invention is a fastening which can be placed and replaced from one side of the tie and which will give the maximum holding capacity with the least deterioration of the tie whether it be old or new.

My invention may be used either with 65 new ties or with old ones which, under the present practice, would be discarded, and will make such old ties serviceable for a long period.

While I will describe my invention in 70 connection with wood ties, it will be understood, that it, and the claims based thereon, are equally applicable to other forms of ties made of a composition and that the invention and the claims apply equally well 75 where the rails are fastened directly to wood structures, such as stringers, beams, floors, sills, girders and the like.

My invention further relates to such a rail tie expansion which is simple and inexpensive.

I have shown in the accompanying drawings an illustrative embodiment of my invention, but of course it is to be understood that my invention is not to be confined simply to the forms illustrated. In these drawings the same reference numerals refer to similar parts.

Figure 1 is a fragmentary transverse vertical section of my present invention, the spike member and spike being shown in side elevation; the spike member being partly broken away.

Fig. 2 is a perspective view of the spike member shown in Fig. 1.

Fig. 3 is a fragmentary side elevation showing my rail tie expansion used with a rail brace;

Fig. 4 is a fragmentary transverse vertical section of Fig. 3 the spike member being 100 partly broken away.

In the accompanying drawing, 1 is any form of T-rail held to the tie 2 which is ordinarily wood and which may be treated or untreated with a preservative. In this tie, if it is a new one, I bore a hole 3 preferably at an incline to the surface 4 of the tie. In this hole I either drive or drop, as the case may be, my rail tie spike member which may be formed in any suitable man-

ner and of any suitable contour, those shown in the drawing, being simply illustrative. In all forms, however, the spike member only contacts with a part of the wall of the 5 hole permitting the rail spike, whether it be a drive spike or a screw spike, to contact with the portions of the hole not in contact with the spike member. I have shown my spike member as being formed of one part 10 which is my preferred construction, it being understood, however, that in all forms of my invention, the spike, whatever its form may be, contacts with some portion of the wall of the tie to expand the rail tie expansion, at 15 the same time that the spike member contacts with other portions of the wall of the same hole.

In Fig. 1, the spike member 5 is provided with an open side 6 with which the screw spike 7 contacts at the same time as it contacts with the wall 8 in the tie 2.

Preferably, though not necessarily, the open side 6 of the spike member 5 is provided with interrupted screw threads 10 to 25 cooperate with the male threads 11 upon the screw spike 7. I also preferably provide the open side 6 with an inclined surface as shown, the cross-sectional area of the spike member 5 being less near the outer 30 end 12 than at the inner end 13.

In this form the spike member 5 is driven or dropped into the hole 3 and the screw spike 7 is then inserted and screwed by turning the angular head 14 of the screw 35 spike, which will cause the screw threads 11 to bite into that portion of the wall of the hole which is not covered by the spike member 5, and at the same time they will coact with the spike member and give a powerful 40 expansion. This expansion serves to compress and preserve both portions of the wall of the hole, that in contact with the spike member 5, as well as that in contact with the screw spike. Not only will this expansion 45 give a powerful grip in the tie 2, and serve to make the tie and the rail 1 act as one member, but this expansion also, in addition to the above function, tends to prevent moisture working into the hole and thereby 50 further preserves the life of the tie.

The hole 3 is preferably bored at an angle to the face 4 of the tie to permit the head 15 of the spike member contacting directly with the incline flange 16 of the T-rail 1.

55 It will, therefore, be seen that in my invention only a comparatively small portion of the wall of the hole 3 is subjected to the action of the screw threads 11 on the screw spike 7, while the greater part of the wall 60 of the hole receives a powerful frictional side thrust by the lateral movement of the spike member. Preferably, though not necessarily, I make the exterior of my spike member plain or I may provide it with projections or corrugations.

In this form of my invention as well as in my other forms illustrated, described and claimed in the parent application above referred to, my rail tie expansion has a greater bearing in the tie than is obtained either by 70 the screw spike or the drive spike. This insures a greater distribution of the strain of the rolling load throughout the fiber of the wood and accordingly less deterioration 75 of the tie. While the screw spike is considered in practice preferable to the drive spike its threads cut up the fiber of the wood and cause it to deteriorate at a much earlier date than if they had not been so cut. By my invention when a screw spike is used, I insure 80 that it will only partially cut up the fiber of the wood and this damage is largely overcome by the tremendous expansion and compression to which the wood in engagement with the screw spike is subjected. 85

It is further observed that the greatest displacement of the wood is at the extreme inner end of the hole which forces a larger aperture at that end than at the mouth of the hole. This causes a dovetail effect which 90 increases the holding capacity of my fastening over other forms of drive spikes and screw spikes which enter or create parallel bores.

In old ties my invention is equally applicable. In such an old tie, in which the spike hole has been so enlarged by constant spiking and respiking, and rotting and tearing of the fiber of the wood, in the hole that, under the present practice would necessitate 100 the tie being discarded as unserviceable and absolutely dangerous, my rail tie expansion will permit this old tie to remain in its position in the road bed, without the delay and labor of removing it and the insertion of a 105 new tie, besides by my invention I save the cost of a new tie.

In such an old tie my spike member 5 may be driven or dropped into the old hole and then the old or a new spike may be used to obtain the requisite expansion and compression of the fiber of the tie. Preferably, in such an old hole, I would use a spike member and a screw spike. If the form shown in Fig. 1, for example, be used, in the old 115 hole by screwing up on the head 14 of the screw spike 7, a powerful expansion would be obtained and one which would so compress the old fiber in contact with the spike member 5 that it would practically give new 120 life to that portion of the wall of the hole, at the same time the reaction from this compression would cause the male threads 11 upon the screw spike 7 to bite powerfully 125 into the other portion of the wall of the hole and into that portion of the wood of the tie which has not rotted or otherwise been rendered unserviceable.

It is therefore, clear that with my invention, a new tie, whether treated or untreated 130

with a preservative, can be kept in the road bed until the fiber throughout the tie deteriorates to such a state as to render it unserviceable for further use instead of discarding it for a local deterioration due, under the present practice, to driving and redriving drive spikes, or positioning or repositioning screw spikes. This is particularly desirable in comparatively expensive ties treated with a preservative which formerly had to be discarded even though they had suffered only local deterioration where the spikes had been used.

It is customary on curves to use rail braces. One form of brace I have shown at 19, Fig. 3. This brace has a strengthening rib 20, and a flange 21 to lie adjacent to the flange 16 of the rail 1.

The tremendous lateral strains which are thrown on the rail braces 19 are transmitted to the tie 2 in the manner I have previously described by the head 15 of the spike member contacting directly with the inclined surface 22 of the rail brace 19. While I have shown a rail brace coöperating with two of my rail tie expansions it is of course to be understood that any number may be used.

Various modifications and adaptations of my invention may be made.

In the form of my invention illustrated the rail 1 is held to the tie 2 by the spike member 5, which is preferably driven by a maul, sledge hammer or any suitable tool into the hole 3 in the tie 2 until the head 15 of the spike member 5 contacts with the flange of the rail 1. This serves to hold the rail to the tie, the spike member acting as an ordinary driven spike.

This holding action is supplemented and perfected by the tremendous expansion and hold of the screw spike 7, when it is screwed home as shown for example in Fig. 1, its head 14 engaging the flange of the spike member and its male threads 11 coöperating with the female interrupted threads 10 in the spike member 5. It is therefore clear that this rail tie expansion consists of a driven spike member, which itself serves to hold the rail to the tie, and also a rotative member which by moving the spike member laterally and by screw action still further serves to positively hold the rail to the tie, be the tie old or new.

If the tie 2 is an old one, in which the hole 3 was the original hole, in which the ordinary form of drive spike has been used, my spike member 5 would tend to somewhat enlarge that hole and compress the old lacquered and broken fiber forming the wall of the hole with which it contacts.

I may in some cases, though not necessarily, provide the inner end of my spike member 5 with a more or less sharp pointed end 17.

Having thus described this invention in connection with the illustrative embodiments thereof to the details of which I do not desire to be limited except as required by the scope of the claims, what is claimed as new and what it is desired to secure by Letters Patent is set forth in the appended claims:

1. A rail tie fastener comprising the combination of a drive spike member having a surface broken away to permit a portion of a screw spike to extend out from the drive spike member and a screw spike adapted to coöperate with the drive spike member and also with a tie through the interrupted or broken away portion of the drive spike member.

2. A rail tie fastener comprising the combination of a drive spike member provided with interior screwthreads and having a surface broken away to permit a portion of a screw spike to extend out from the drive spike member, and a screw spike adapted to coöperate with the interior screwthreads of the drive spike member and also with a tie through the interrupted or broken away portion of the drive spike member.

3. A rail tie fastener comprising the combination of a drive spike member having a surface broken away to permit a portion of a screw spike to extend out from the drive spike member, and provided with a comparatively sharp point to assist in seating in a hole in a rail tie, and a screw spike adapted to coöperate with the drive spike member and also with a tie through the interrupted or broken away portion of the drive spike member.

4. The combination of a rail tie spike member having a flange to engage with the flange of a rail and having an open side to permit a rail spike to engage directly with the rail tie spike member and with the rail tie, and a rail spike having a head engaging with the flange of the rail tie spike member.

5. The combination of a rail tie spike member having a flange to engage with the flange of a rail and having an open side to permit a rail screw spike to engage directly with the rail tie spike member and with the rail tie, and a rail screw spike having a head engaging with the flange of the rail tie spike member.
